UNITED STATES PATENT OFFICE

HOWARD W. LEWIS, OF NEWARK, NEW JERSEY

AUTOGRAPHIC REGISTER

Application filed January 4, 1928. Serial No. 244,464.

The present invention relates, generally, to apparatus for handling several sheets of paper simultaneously one over the other with carbon between for making an original and 5 copies of sales memoranda and the like.

The invention relates more particularly to apparatus of the kind indicated adapted for holding several rolls of paper in such a manner that they can be drawn out or unrolled 10 by hand in superimposed sheets with the rolls themselves serving as weights to tension the sheets so that they will lie smoothly one over the other.

Objects and advantages of the apparatus 15 of the invention will be apparent from the following description of an embodiment of the invention and from the drawings illustrating the same; and the invention also consists in the various devices and arrangements 20 and combinations of parts set forth in the appended claim.

In the drawings, Figure 1 is a longitudinal elevational view in section showing a device embodying the invention; Figure 2 is a plane 25 view of the same; and Figure 3 illustrates the individual sheet cut from the roll of paper used in the form of the invention illustrated.

Referring now to the drawing, the reference character 1 indicates a longitudinal casing 30 of wood or sheet metal having a cover 2, preferably of metal, thereon which is hinged across one end by the pins 4, 4 carried by said casing and passing through respective flanges 6, 6 formed along longitudinal edges of said 35 cover 2 and overlapping the sides of said casing 1. On the inside said casing 1 carries supporting and guiding members 8, 8 in pairs arranged in a longitudinal row with one of each pair mounted on opposite walls in trans- 40 versely aligned relation with each other.

Each of said members 8, 8 at its forward part is vertical or nearly vertical and at the bottom inclines backwardly and downwardly for a substantial distance. Each pair of the 45 members 8, 8 serves as support for a roll of paper transversely positioned in said casing 1. A roll of paper so positioned tends to roll downwardly on its supporting members 8, 8, and the vertical parts of rearwardly adjacent 50 pair of members 8, 8 will serve as stops to

limit the movement of a roll on its supports. In the case of the last pair of supports at the back, the back wall 10 of said casing 1 will serve as the back stop.

Said cover 2 has at its forward end an opening 12 of a width substantially that of paper rolls suitable for support by said members 8, 8 in the manner described, and of a substantial length along the length of said cover 2. At their forward ends the side walls 14, 14 55 have formed therein longitudinal notches 16, 16 adjacent said flanges 6, 6 which latter at their portion adjacent said notches 16, 16 support the rollers 20, 20 which are arranged transversely and in a longitudinal row along 60 said flanges 6, 6. There are as many of said rollers 20, 20 as there are of said support members 8, 8. Rearwardly from said opening 12 each of said flanges 6, 6 has struck out from its edge portion a pair of longitudinally 65 spaced apart tabs 22 and 23 each of which is bent upwardly and aligned parallel with and in spaced apart relation with its respective flange 6. On each flange 6 the respective tabs 22, 23 carry a bar 24, 24 extending therebetween and inserted with its respective ends between tabs 22, 23 and the flange 6, said 70 tabs serving as spring friction means for holding the bars in place. At the rear and beyond said tabs 22, 23 said cover 2 carries a 75 downwardly sloping portion 26 which carries the transversely spaced apart studs 28 which project substantially at right angles therefrom. Beyond said studs 28, 28 said cover portion 26 bends downwardly at the angle 80 and then upwardly at the angle and terminates in a paper cutting edge 30, which is aligned with the surface of said portion 26.

The rolls of paper 32, 32 are mounted on 85 said support members 8, 8 and are divided longitudinally into sheets 33, 33 defined by the lettering and lining printed thereon and each of said sheets 33, 33 is provided near its top with a pair of transversely spaced apart holes 34, 34 adapted to fit over and engage respective ones of said studs 28, 28 in a manner 90 and for the purpose hereinafter more fully described. Each of said rolls of paper 32, 32 is mounted so that the winding is in a direction 95 which is upwardly and toward the front 100

of the casing 1, and each roll has a portion unwound and extending therefrom forwardly and upwardly to and over a respective one of said rollers 20, 20 from which they extend, 5 one in superimposed relation over the other, along the top surface of said cover 2 to said studs 28, 28 where said holes 34, 34 are fitted over and engage respective ones of said studs 28, 28, the holes 34, 34 of each sheet being 10 aligned with and registering with corresponding holes in the other sheet.

Interleaved with adjacent ones of said sheets 33, 33 between said tabs 22, 23 are the carbon papers 36, 36 whose edges are turned 15 down against respective ones of said flanges 6, 6 and held in place in secured relation by said bars 24, 24 which are positioned thereagainst with their respective edges held by said tabs 22, 23.

20 In the use and operation of the embodiment above described to illustrate the invention and shown in the drawings, a sales or other memorandum having been made on the sheets 33 next adjacent said studs 28, 28 the 25 sheets are removed by grasping their ends adjacent said studs 28, 28 and pulling backwardly until a new set of said holes 34, 34 comes adjacent said studs 28, 28 over which they are fitted and adjusted and the used 30 sheets 33, 33 are torn off against said cutting edge 30. The unrolling of the paper from said rolls 32, 32 causes the latter to roll up the inclined portions of said support members 8, 8 so that when a new set of said holes 34, 34 is fitted over said studs 28, 28 and the paper released, the weight of said rolls 32, 32 tends to cause them to move downwardly on 35 the inclined portions of said support members 8, 8 and rewind whereby the unrolled 40 portions will be pulled forwardly over the top 2 of the casing 1. But the edges of said holes 34, 34 through engagement with said studs 28, 28 will limit the movement of said rolls downwardly on said support members 45 8, 8 whereby the paper is held under tension on said cover 2 and between said carbon papers 36, 36. It will be clear then that since the said sheets 33, 33 are of considerable 50 length there will always be sufficient pull to hold said paper under tension on said studs 28, 28. Also since the inclined portions of said support members 8, 8 are of considerable 55 length the said holes 34, 34 can be pulled a considerable distance beyond said studs 28, 28 and yet have the weight of the rolls pull the paper back to bring said holes into 60 tension engagement with said studs 28, 28 when they are set in engagement thereover. The vertical portions of said members 8, 8 serve 65 in this case to limit the forward movement of said rolls as they are unwound.

The said members 8, 8 are shown in the drawings as being made separate from but fixed to the side walls 14, 14 but where the side walls are made of sheet metal the sup-

ports 8, 8 can be supplanted by similarly formed inward indentations in said walls. Also a piece of sheet metal or other material can be formed to extend entirely across said casing and defining vertical and inclined surfaces equivalent to those of members 8, 8 on which said roll of paper 32, 32 move and rest and against which they engage. 70

It is to be understood that various other changes, omissions and substitutions can be 75 made in the various devices and combinations and arrangements of parts hereinabove set forth and described without departing from the scope of the invention as set forth in the appended claim. 80

I claim:

In an apparatus for holding a plurality of rolls of paper to be drawn out in sheets with carbon paper between for making duplicate memoranda, a writing plate having a main portion and a downwardly offset rear portion, a transverse cutting edge extending outwardly from said rear portion, a pair of spaced studs extending outwardly from said rear portion adjacent said cutting edge, said cutting edge and said studs being positioned below the surface of the main portion of said writing plate and arranged so as to allow the free uninterrupted movement of sheets parallel to and along said main portion and above said rear portion but being adapted to operatively engage said sheets upon a slight downward movement of the free end of the latter. 95

In testimony, that I claim the invention set 100 forth above I have hereunto set my hand this 30th day of December, 1927.

HOWARD W. LEWIS.
